UNITED STATES PATENT OFFICE.

CLARENCE A. SCHUBERT, OF FINDLAY, OHIO.

MATERIAL-HANDLING APPARATUS.

Application filed January 10, 1924. Serial No. 685,343.

While this apparatus is designed primarily for the handling of coal, it is also adaptable for the handling of various other materials such as ore, gravel, sand and the like. Also while it is shown as being used for the hoisting of fragmentary materials, nearly directly upwardly, it will be understood that it may be used horizontally or at intermediate angles. I, therefore, do not wish to be limited to the specific structure or use illustrated in the accompanying drawings which are to be understood as suggestive only and which show a preferred embodiment of my invention.

Among the various objects of my invention are to provide efficient apparatus of the character stated; to provide easily operated mechanism of the character described; to produce a device by which fragmentary materials may be efficiently handled; to improve upon the operating mechanism of apparatus of the character described; to provide hoisting mechanism which will maintain a plurality of hoisting cables taut, constantly, which ever direction the hoisted article may be moving; and such other and further objects, advantages and capabilities as will hereafter more fully appear and as are inherent in the construction disclosed.

My invention further resides in the combination, construction and arrangement of parts illustrated in the accompanying drawings and, while I have shown therein a preferred embodiment of my invention, I desire the same to be understood as illustrative only and not as limiting said invention.

In the drawings annexed hereto and forming a part hereof Fig. 1 is a fragmentary vertical section of an installation showing one adaptation of my present invention; Fig. 2 is a diagrammatic view, in elevation, showing the threading of the various cables by which the car is operated; Fig. 3 is a similar view showing the car in another position of use; Fig. 4 is a similar view showing the car in still another position of use; Fig. 5 is a similar view showing the parts in the same relation as in Fig. 4 except that the bucket carried by the car is in dumping position; Fig. 6 is a fragmentary plan view showing the relationship of the car, tracks and various cables; Fig. 7 is a plan view of the operating mechanism whereby the

cables are operated; Fig. 8 is a rear view of the apparatus shown in Fig. 7; Fig. 9 is a longitudinal sectional elevation in the plane of the main shaft of the operating mechanism; Fig. 10 is a vertical transverse section substantially along the plane indicated by the line 10—10, Fig. 7; Fig. 11 is a vertical transverse sectional view substantially along the plane indicated by the line 11—11, Fig. 9; Fig. 12 is a somewhat enlarged vertical section of a portion of the apparatus in bucket loading position; Fig. 13 is a view similar to Fig. 12 but showing the car being moved out of loading position; and Fig. 14 is a transverse section showing this apparatus in use in conjunction with a plurality of tracks and filling hoppers.

Referring more in detail to the annexed drawings, R represents a storage reservoir or a plurality of such reservoirs in which fragmentary materials are to be stored. Tracks T¹, T² and T³ serve to carry a car C from its loading position shown in Figs. 1, 12, 13 and 14 to the interior of the storage reservoirs where the materials are lowered to near the surface of the material already in the reservoirs and there dumped. The car is operated by a plurality of cables 1, 2 and 3 passing over suitable guiding sheaves or rollers to the operating mechanism or hoist H. Beneath the tracks 5, adapted to receive railroad cars, is a loading hopper 6 having in its lower portion a gate 7, the effective opening of which is regulated by an adjustable member 8. This is operated by a rope or other suitable adjusting means 9 connected to an actuating mechanism 10. Mounted adjacent the gate 7 is a closure member 11 to which is connected an operating arm or arms 12 carrying a member 13 to be engaged by the bucket 14 of the car C, on its downward trip. As a result of this, the operating members 12 acutate the closure member 11 to open the passage from the loading hopper 6. The materials contained in this hopper will then move through the opening 7 into the bucket 14 until the same is full. Upon the car C being pulled away from loading position the weight 15, through the cable 16 will cause the closure member 11 to turn upon its pivot and close the discharge opening from the hopper.

6. By suitable operation of the hoisting mechanism H, the car will be caused to move up on the track T^1 , along the track T^2 and downwardly along one of the tracks T^3 into 5 a reservoir R. Here the bucket 14 is turned upon its trunnions by suitable actuation of the cable 3 to cause dumping of the materials in the bucket. The specific construction of the car C is not shown or described herein 10 since the same is fully disclosed in a prior application filed by the present applicant and copending herewith. It is therefore not considered necessary to show this construction in the present application.

15 Reference will now be made to Figs. 7 to 11 for a complete understanding of the hoisting mechanism, before explaining in further detail the operation of transferring materials from one location to another. In a 20 suitable frame 19 is mounted a main shaft 20 carrying a plurality of winding drums 21, 22 and 23, whose operations are controlled by a plurality of clutches 24, 25 and 26, whose functioning is controlled by operating members 27, 28 and 29, as will be clear 25 from a study of Figs. 7, 8 and 9. Operating upon flanges 31 and 32 of drums 21 and 22 are brake bands 33 and 34, whose functioning is controlled by levers 35 and 36. 30 Referring now to Figs. 7 and 8, a motor or other source of power, M, drives a gear 37 meshing with a gear 38 upon a shaft 39. The gear 38 in turn meshes with a gear 40 carried by a shaft 41. Upon this latter 35 shaft there is loosely mounted a gear 42 which meshes with a gear 43 secured to the shaft 20 in any suitable manner, as by a key 44. Rigid with the gear 42 is a drum 45 of clutch 24 by means of which rotation of the 40 shaft 41 is transmitted to the gears 42 and 43 and from this to the main driving shaft 20. The drum 21 may either be secured to the gear 43 or the shaft 20 or both as shown in Fig. 9. It will therefore be evident that 45 when the power is applied and the clutch 24 is thrown in the cable 1 will be wound up on the drum 21.

As will be seen from Fig. 9, drums 22 and 23 are loose on driving shaft 20, as is also 50 gear 48 which is driven by gear 49 on shaft 39. From this it will be seen that when the power is applied to gear 38, shaft 39 will be operated and will drive gear 48 thru gear 49. It will also appear from this that 55 shaft 39 rotates constantly in one direction whenever the motor M is running.

The gear 48 is provided with flanges 50 and 51 to cooperate with flanges on drums 22 and 23 to form the clutches 25 and 26. 60 A plate 52, as shown in Fig. 9, is loosely mounted upon the shaft 20 and presses against the end of drum 22 and its flange 53. Projecting from the plate 52 are pins 54 which extend slidably through the web 55 65 of the gear 48. Between the web 55 and the

plate 52 and surrounding the pins 54 are springs 56 which press the plate against the end of the drum 22. A certain amount of friction exists therefore between the plate 52 and the drum 22, together with its flange 53 and tends to cause the rotation of the drum 22 in the same direction that the gear 48 rotates. From this it will appear that the tendency is for the cable 2 to be kept 70 constantly taut and that whenever there is sufficient resistance to prevent the rotation of drum 22 there will be slippage between the plate 52 and the drum. There is normally not enough friction between the plate 75 and drum to cause lifting of the car C but this can be accomplished by operating the lever 28 which causes the drum 22 to be moved to the right, as shown in Fig. 9, thus 80 engaging the parts of clutch 25. It will be clear that simultaneous winding may take 85 place with drums 21 and 22 or that one may wind and the other unwind.

Resting against the end of drum 23 and its flange 63 is a plate 62 loosely mounted upon the shaft 20. Projecting from the 90 plate 62 are pins 64 which extend through the plate 65 secured to the shaft 20, as by a key 67. Surrounding the pins 64 and exerting tension between the plates 62 and 65 are springs 66. It will appear from this 95 that the normal tendency of drum 23 is to rotate in the same direction as drum 21, since both are driven by the shaft 20. However, if the lever 29 is actuated to throw in the clutch 26, there will be sufficient friction 100 between the flange 51 and its cooperating member of clutch 26 so that this normal tendency to rotate in one direction may be overcome and rotation in the opposite direction be positively caused. It thus appears 105 that drum 23 may be caused to rotate in the same direction as or in a counter direction to the drum 21. The same is true also with respect to the drum 22. The importance of these various movements will be 110 more apparent hereinafter.

Reference will be made now more particularly to Figs. 7 and 10, in the latter of which a pin 70 is shown in section. This pin is mounted in one of the cross members 115 of the frame 19 and supports oscillatably the dog 71. This dog 71 is actuated upon its pivot by means of the link 72 connecting it with the handle 73. This dog is capable of engaging the teeth 74 upon the inside of flange 31. This can be used to hold the car C at any desired height and prevent the same from moving downwardly along the tracks T^1 or T^3 .

Adjusting means 75 is provided for adjusting the tightness or looseness of the brake band 33 in its normal or loose position. A spring 76 engages the lever 35 and normally holds it in raised position to keep the brake band 33 loose, this spring being 120

secured to one of the cross members of the frame. A similar adjusting means 77 is provided in connection with brake band 34, as shown in Fig. 8.

5 In the application of my invention shown in Fig. 14 of the drawings, a plurality of parallel or substantially parallel tracks 5 pass over a series of loading hoppers 6 in which the discharge mechanism is the same 10 as that heretofore described except that provision is made for getting the cross bars 13 out of the way so that they will not be hit by the car C, if it is desired to pass any of the loading hoppers and load from one farther along. This may be accomplished in 15 any desirable way but is shown at the right of this figure as having been accomplished by moving the cross bar 13 up towards the upper end of the levers 12. In this position 20 the cross bar is high enough so that the car in coming down will pass between the levers 12 and below the cross bar 13, thus passing on to come into contact with the next bar 13 which is near enough the end of the lever 12 25 so that it may be hit by the top of the bucket, thus causing the member 11 to swing upon its pivot and open the gate 7 for the exit of materials. There is a further slight modification in this construction in that the 30 cable 2 in passing from the car frame goes to a pulley or roller 78 so that when the cable is pulled the car will be moved back under tracks farther away from the hoisting apparatus. Of course, it is obvious that the 35 pulley 78 must be secured near the remote wall of the farthest loading chamber, if the apparatus is to be operated to the fullest extent without shifting this pulley. It may, however, be detachable and be moved from 40 one position to another, if desired, when shifting from one loading chamber to another for loading purposes. This is not, however, considered the more desirable arrangement.

45 In Fig. 8, the shaft 39 is shown as extending beyond the gear 38 sufficiently for the attachment of another gear thereon. By moving the motor M farther away from the hoist mechanism, mounting a gear upon the 50 end of the shaft 39 of a size different from gear 38 and then mounting the motor so that gear 37 will mesh with the added gear, the gear ratio may be changed and the speed of the hoist correspondingly increased or decreased. This is ordinarily not necessary but 55 may be indulged in where it is thought desirable to have greater lifting power or a more rapid rate of travel.

60 In the drawings arrows are used in connection with certain shafts and gears to indicate the direction of rotation thereof, solid arrows indicating that they rotate continuously while the motor is in operation and dotted arrows that rotation is intermittent.

65 This invention has been described in con-

nnection with an installation for the hoisting of materials, especially coal, but it is to be understood that the same equipment, with slight changes, could be used on horizontal or nearly horizontal tracks, and such a construction is therefore comprehended within the scope of the claims appended hereto.

Operation.

In use the car C is moved to loading position as shown in Figs. 1, 12 and 14 and, in so doing, the gate 7 is opened permitting the material in the loading hopper 6 to be discharged into the bucket 14 until the same is full. Then, with all brakes off and clutches 75 out of engagement, handle 27 is actuated to throw clutch 24 into engagement. The operation of the motor then causes drum 21 to be turned so that cable 1 is wound up thereon. At the same time, rotation of shaft 39 and gears 49 and 48 causes plate 52 to turn in the opposite direction from shaft 20. This causes drum 22 to take up all slack in 80 cable 2 and keep the same constantly taut. It will be apparent that rotation of the shaft 20 will cause corresponding rotation of plate 85 65 and, consequently, drum 3. This would cause the unwinding and slackening of cable 3. This can be overcome by actuation of the lever 29 which will cause engagement of clutch 26, resulting in the turning of drum 23 in the opposite direction. In this way 90 cable 3 may be kept taut until the car has passed the hoisting apparatus and then it will be unnecessary to pay further attention to this cable, the same being unwound at the same rate of speed as cable 1 is being wound up. During this operation it is unnecessary 95 to pay any attention to cable 2 by reason of the fact that gear 48 and plate 52 tend to keep the same taut at all times. By reason of the fact that the cable 1 passes to the extreme end of the series of storage reservoirs, it will be possible to pull the car C to any 100 one thereof. By opening a switch in the track T², as shown at S in Fig. 1, the car can be permitted to pass downwardly into any one of the reservoirs. As soon as the car reaches the switch S and starts downwardly thereon, it will be necessary to apply 105 the brake 34 on drum 22, controlling cable 2, so that it can be prevented from unwinding too rapidly. At the same time, clutch 24 is disengaged and brake 33 may or may not be used in conjunction with brake 34 as desired. It will be apparent that during the 110 first part of the operation described above the cable 2 is being wound up on drum 22 and that during the time that the car is moving along track T² this cable is being 115 unwound. This unwinding will continue as the car moves downwardly on track T³ into the interior of the reservoir R. When the car has reached a position so that the bucket 120 is nearly in contact with the material already 125

in the reservoir, handle 29 is actuated to cause engagement of clutch 26. This causes cable 3 to be wound up on drum 23, thus occasioning the dumping of the bucket. By keeping the clutch 26 engaged, the car can be lifted on the track T^3 and pulled along the horizontal track T^2 until it reaches the track T^1 . From here on it will be necessary to use either brake 33 or 34 to gradually lower the car to loading position.

It will be observed that when the cable 3 is being wound up on drum 23 the friction between plate 62 and the end of the drum will cause the shaft 20 to rotate in the same direction as the drum, unless clutch 24 is engaged to cause winding of the cable 1. It will be understood that when the car C leaves the track T^2 and starts down on the track T^1 , the weight of the car will carry it to loading position, opening the gate 7 on its way. In a construction such as is shown in Fig. 14, the car may be drawn back under the tracks as far as it may be desired by engaging the clutch 25 to wind the cable 2 upon the drum 22. It will be obvious that means should be provided for keeping the car on the track T^2 when the car is passing down into or up out of a reservoir R. No such means is shown in connection with this application as the same will be understood without further reference thereto. One such means is shown in my copending application referred to above. It will also be understood that any one of several means may be adopted for this purpose.

Attention should perhaps be called to the fact that drum 22 is geared faster than drums 21 and 23 and so will run faster than either of these except when drum 23 is clutched to gear 48 so that it runs in the same direction and at the same speed as drum 22. It is believed that the arrangement of the guiding sheaves for the various cables will be evident from the drawings without being particularly specified herein.

It is, of course, understood that the specific description of structure and operation set forth above may be departed from without departing from the spirit of my invention as set forth in this specification and the appended claims.

Having now described my invention, I claim:

1. A system for conveying material from

a pit into a tower comprising a carrier, a carrier track, flexible means for propelling said carrier toward said tower, a second flexible means for lowering said carrier into said tower to a plurality of predetermined levels, and a third flexible means for unloading said carrier at any of a plurality of predetermined levels within said tower.

2. A system for conveying material from a pit into a tower comprising a carrier, a carrier track, flexible means for propelling said carrier toward said tower, a second flexible means for lowering said carrier into said tower to a plurality of predetermined levels, and a third flexible means for unloading said carrier at any of a plurality of predetermined levels within said tower and for raising said carrier out of said tower.

3. A system for conveying material from a pit into a plurality of towers comprising a carrier, a carrier track, flexible means for propelling said carrier to the top of each of said towers, a second flexible means for lowering said carrier into any of said towers to a plurality of predetermined levels, and a third flexible means for unloading said carrier at any of a plurality of predetermined levels.

4. A system for conveying material from a pit into a plurality of towers comprising a carrier, a carrier track, flexible means for propelling said carrier to the top of each of said towers, a second flexible means for lowering said carrier into any of said towers to a plurality of predetermined levels, and a third flexible means for unloading said carrier at any of a plurality of predetermined levels and for raising said carrier out of said tower.

5. A system for conveying material from a pit into a plurality of towers comprising a carrier, a carrier track, flexible means for propelling said carrier to the top of each of said towers, a second flexible means for lowering said carrier into any of said towers to a plurality of predetermined levels, and a third flexible means for unloading said carrier at any of a plurality of predetermined levels and for raising said carrier out of said tower, all of said means being propellable and controllable from one station.

In witness whereof, I hereunto subscribe my name to this specification.

CLARENCE A. SCHUBERT.
